(57) **CLAIM**

The ornamental design for a flip spout bottle, as shown and described.

DESCRIPTION

FIG. 1 is a front upper perspective view of a flip spout bottle in a closed configuration, showing our new design;

FIG. 2 is a front lower perspective view of the flip spout bottle of FIG. 1 in the closed configuration;

FIG. 3 is a front view of the flip spout bottle of FIG. 1 in the closed configuration;

FIG. 4 is a rear view of the flip spout bottle of FIG. 1 in the closed configuration;

FIG. 5 is a left side view of the flip spout bottle of FIG. 1 in the closed configuration;

FIG. 6 is a right side view of the flip spout bottle of FIG. 1 in the closed configuration;

FIG. 7 is a top view of the flip spout bottle of FIG. 1 in the closed configuration;

FIG. 8 is a bottom view of the flip spout bottle of FIG. 1 in the closed configuration;

FIG. 9 is a front perspective view of the flip spout bottle of FIG. 1 in an open configuration;

FIG. 10 is a front lower perspective view of the flip spout bottle of FIG. 1 in the open configuration;

FIG. 11 is a left side view of the flip spout bottle of FIG. 1 in the open configuration; and,

FIG. 12 is a top view of the flip spout bottle of FIG. 1 in the open configuration.

The broken lines in the figures illustrate portions of the flip spout bottle that form no part of the claimed design.

1 Claim, 9 Drawing Sheets
